UNITED STATES PATENT OFFICE.

MERION LESLIE PREBLE, OF AUBURN, MAINE.

LAST ANALYZER.

Application filed March 11, 1919. Serial No. 281,946.

To all whom it may concern:

Be it known that I, MERION L. PREBLE, a citizen of the United States, residing at Auburn, county of Androscoggin, State of Maine, have invented certain new and useful Improvements in Last Analyzers, of which the following is a specification.

In the manufacture of shoes much difficulty has been experienced in the past in practically applying the standardizations which have been worked out and generally adopted by manufacturers.

My present invention involves a system of application or a basis of utilization of such standards and affords both a manner and a means of critically or analytically dealing with shoe lasts whether for the purposes of the original production of lasts or for the correction of lasts found upon test to require modification.

In considering this invention it is necessary to bear in mind that the last is initially a foot model, secondly, a basis of shoe pattern, and, third, a construction form on which the uppers cut from the pattern produced from the last are made up for embodiment into the shoe.

I have analyzed the difficulties heretofore experienced by the trade as having origin principally in the inherent nature of the last. The last by its very nature is what we may call a dismounted or detached body of indefinite base and of a relation to the plane of tread varying according to the style of shoe which the manufacturer may elect to build on the last. In other words, until a last has its position definitely determined as to the plane of tread, i. e., to the plane of the heel and sole of the shoe which is to be made on it, the analysis of the correctness of its proportion and dimensions cannot be definitely determined. Even if upon test a last is found to be incorrect after having been tried out, such defects can not at present be readily or accurately or scientifically specified for correction.

In order to locate and determine the points to be included in accurate measurement of ball, waist, instep or heel, the marking on the last of certain points has been established. These bear relation to the longitudinal dimensions of the last. The location of such points, however, as above pointed out, vary in different positions in which the last might be held relative to the horizontal plane.

My invention contemplates broadly the establishment of a last in a predetermined or desired position to the horizontal. It also contemplates the scaling of certain points of the last relative to such position. It provides for the marking of the locating points for standard measurements and throughout is permissive for such adjustments, observations and measurements, as to definitely determine both points of prevention and elements of error so as to establish between the manufacturer and the last maker a definite basis from which each may work without the possibility of misunderstanding or misconstruction.

Marking devices for lasts have heretofore been provided, but none so far as known to me effect such marking with reference to the ultimate position of the shoe as influenced by height at breast, wedge of heel, or toe spring.

In so far as my invention involves novel procedure, I shall treat it under the double aspect of verification of original construction, and second, analysis of changes necessary for modification or criticism of error. All this may be advantageously discussed in connection with the means which makes the above practice possible. For the purposes of the present application, I have shown and described a device which I have found well adapted to all the practical phases of the foregoing and which in itself, while being an illustrative embodiment of my invention, is a practical and useful means to the end.

In the drawings:

Fig. 1 is a side elevation of apparatus for the practice of my invention, showing a last in position.

Fig. 2 is a side elevation partly in section of the same.

Fig. 3 is a view of a section on the line 3-3 of Fig. 1.

Fig. 4 is a view taken of a section 4-4 of Fig. 1 looking in the opposite direction, and Fig. 5 is a plan view of my apparatus.

My apparatus consists of a bed or way 1 having turned up portions 2 and 3 at opposite ends thereof to which are bolted leg members 4 and 5. The way 1 is formed with a shouldered slot 6 as shown in Fig. 4.

The open frame 7 is adjustably mounted on a base portion 8 which bears against the lower face of the way 1, being held and guided thereon by a slide piece 9 which fits

within the slot 6 and lies flush with the top of the way. The piece 9 is bolted through the open slotted bottom of the way 1 into the piece 8.

5 The open frame 7 is guided on the member 8 in a suitable central way and is adjustable thereon by a screw 9¹ turned by a knurled head 10 and threaded into the base portion 7¹ of the frame 7. At the upper part 10 of the open frame 7 is a slideway formed as a bracket 72 slotted longitudinally to receive a clamp screw 10¹ which is tapped into the base 11 of the instep marker 19 and permits it to be adjusted longitudinally as 15 a whole. The bracket plate 72 and base 11 are scaled at s⁵.

The plate 11 is provided at one end with an up-turned flange 12 within which is screwed, a guide sleeve 13 held by a clamp 20 nut 13¹ and through which a squared scale bar 17, scaled as indicated at S², is guided, see Figs. 2 and 4. The sleeve 13 is externally threaded as indicated at 13^a, Fig. 2, to cooperate with an internally threaded sleeve 25 by means of which the bar 17 may be adjusted longitudinally upon rotation of the sleeve 15, said bar having bearing in said sleeve 15 at its rear end as indicated at 16, Fig. 2. The bar 17 is carried forward and 30 terminates in a T-shaped head 18 slotted at 18¹ and scaled at W¹ for the lateral adjustment of the instep marker 19. The brad 19 is shouldered at 20 and supported by a spring 21 contained within the tubular member 22. The tube 22 is undercut at 23 to fit flush within the laterally undercut slot of the head 18, being clamped in desired adjusted position by the knurled nut 24. Through these various adjustments the brad 35 40 19 may be accurately positioned over the cone of the last L as indicated in Fig. 1.

The member 8 is carried back underneath the way 1 and is laterally channelled as indicated at 25¹, Figure 2, to receive a pair of slide pieces 25—25. Each of these pieces 25 has an up-turned end 26 slotted at 27 to adjustably receive a block 28 which contains a brad 29 which may be brought into contact with the sides of the last to mark the proper 50 position for ball measure. The two slide pieces 25—25 are pushed into the lateral groove in the member 8 from opposite sides and are reversible in such way for the marking of the right and left of a pair of lasts. 55 For reversal they are simply withdrawn and are positioned side by side in the way reversed so as to bring the one which was in advance of the other to the rear of the other in second position.

60 The open frame 7 with its slide member 8 is moved and adjusted along the way 1 by a threaded feed bar 30 turned by a milled head 31, said feed bar being threaded through the base of the up-turned portion 2 of the way 1. The end of the threaded bar

30 is swiveled at 32 into the slide piece 9 which is bolted as previously described to the block 8. The movements of the elements carried by 7 and 8 by the adjustment of feed bar 30 are relative to a size scale 70 S⁶ as appears in plan view in Fig. 5. This determines for the given size a proper position of the opposed prick points 29.

As shown in Fig. 5 of the drawings there are three sets of scales S⁶, one for men and 75 boys indicated by the arrow M, one for women indicated by the arrow W, and one for misses, children and infants indicated by the arrow C, Fig. 1. The slide bar 17 for determining the position of the instep marker 19 is scaled to read at the clamp nut 13¹ of the sleeve 13. Inasmuch as the height of the heel varies the position of the ball measure, it becomes necessary to provide such 80 readings on the block 9 so as to secure accuracy on the way scale. This amounts to a setting off of the element of variation and I therefore provide corresponding markings on the plate 11 relative to a mark on the plate 72 by which a required additional amount may be set off so that the reading of the scale S² on the graduated bar 17 at the clamp nut 13¹ of the sleeve 13 will show the proper size for any given height of heel. 85

Guided on the way 1 is a block 40 held in the guide way 6 by superimposed slide piece 41 bolted through the slot of the guide way into the block 40. The block 40 carries in a vertical way a toothed bar 42 with a T-shaped head 43 at its upper end. The toothed bar 42 is supported, raised and lowered in the block 40 by a pinion 44 on a shaft 45 on which is carried a ratchet wheel 46 engaged by a pawl 47. This permits the adjustment of the support 42 to any height 105 of heel desired. The head 43 supports the last at the breast of the heel.

The block 41 has a pointer mark which reads on a scale S⁴ on the upper face of the way 1. This scale indicates the proper position longitudinally of the way 1 of the breast of the heel for given size of shoe. 110

At the opposite end of the machine from the knurled bar head 31 and formed in the up-turned end 3 is a slideway 50 in which is guided a block 51 on which there is a stepped piece or shoulder 52. The block 51 is adjusted vertically in the slideway by a screw 53 swiveled at 54 and threaded through the block 51 so as to raise or lower it. The proper amount of wedge for the last in question is determined by reading the height of the shoulder 52 on a scale S³ and taking differences between that and the scale S¹ on the bar 42 read in the level of the way 1. 115 120

Slidably mounted on the way 1 is member 60 having an upright 61 on which is a scale S. This upright 61 may be pushed up to the toe of the last as indicated in Fig. 1 and the spring of the toe or height of the lowest 130

portion of the tip of the toe above the plane of the way 1 on which the ball of the last is rested may be read.

In the practice of my invention this device is employed as follows: When a manufacturer makes selection from the different styles of lasts submitted by the last maker, he has then to determine whether the last requires any modifications to make it conform to his own standards.

To this end he places the last in such a machine as shown in the drawings with ball resting on the way 1 and with the heel raised by the head 43 to a proper height at the breast for the heel which he desires that last to carry. The shoulder 52 is then run up under the heel plate at the back of the last. The scale S^3 is then read relative to the scale S^1 , the difference indicating whether the last requires more or less wedge in the heel or is all right. The scale S is then slipped up to the toe of the last and the amount of spring of the toe determined. This again enables the manufacturer to immediately determine whether the spring is all right or whether he requires more or less spring in the toe of the last which he is about to order. It is then desirable to verify the last as to the usual standard of measurement.

The central elements 7 and 8 are adjusted horizontally of the slideway having been set for the given size of the last and the pieces 25 having been suitably adjusted. The prick points 29 are impinged against the opposite sides of the last thus indicating the proper place at which the ball measurement should be taken. The point 19 having been brought by suitable adjustments so that the size reads off correctly for the height of the heel, the point 19 is then impinged upon the last provided that it lies directly over the cone of the last. If it should be found that the point did not center on the cone of the last, then the point may be adjusted and the amount and direction of error from the standard for which the machine was set noted. This enables a manufacturer to instruct the last maker to move the cone of the last which he is going to make, either out or in. With the point 19 adjusted for the proper size of heel, the last is punched to indicate the proper point at which the heel and instep measurements should be taken.

By similar use of the machine the examiner is able to test and verify that these corrections have been carried out by the last maker. If corrections have not been carried out he is able to detect at once and liability is thrown on to the maker for lasts not in accordance with specification.

With such a machine and any reasonable amount of care, the last maker can be able to supply lasts absolutely to specification.

It is of corresponding value to the last

maker inasmuch as it enables him to get definite and specific specifications from his customers and properly apply them and thus avoid any liability on his part.

While the uses above pointed out are at present considered to be the most important, various other uses may and doubtless will develop in the industries. In like manner, while the machine shown has been found well adapted to the industry, various modifications in its form and construction and in arrangement of parts may all be made without departing from the spirit of my invention if within the limits of the appended claims.

What I therefore claim and desire to secure by Letters Patent is:

1. In a device of the class described, a base comprising a slide way, a scaled heel marker at one end thereof, a scaled support for the breast of a last adjustable on said way relative to said heel member, and a scaled toe member mounted on said way for relative adjustment to said heel member, a slide piece on said slide way, lateral markers reversibly mounted in said piece, an open frame vertically adjustable on said slide piece, a marker bar longitudinally adjustable parallel to said way, a head on said bar and a marker point adjustable laterally of said head.

2. In a last analyzer, a scale provided support for the last at the breast of the heel, and a scale provided support for the heel at the back of the last readable with reference to the scale of the first-named support to indicate the wedge of the heel.

3. In a last analyzer, a scale provided vertically adjustable support for the last at the breast of the heel, and a scale provided vertically adjustable support for the heel at the back of the last readable with reference to the scale of the first-named support to indicate the wedge of the heel.

4. In a last analyzer, a scale provided support for elevating the last to the height of the heel that the shoe will carry, and a scale provided support engageable under the heel at the back of the last and readable with reference to the scale of the first-named support to indicate the wedge of the heel.

5. In a last analyzer, a scale provided support for elevating the last to the height of the heel that the shoe will carry, a scale provided support engageable under the heel at the back of the last and readable with reference to the scale of the first named support to indicate the wedge of the heel, and a scale adjustable against the toe of the last to indicate the spring of the toe.

6. A device for last analysis comprising a support for the last at the ball thereof a support for the last at the heel thereof, a scale associated with said last named support, a third support to engage under the

- heel plate at the back of the last, and a scale associated with said third-named support and comparable with said first-named scale to indicate the wedge of the heel.
7. In a last analyzer, a base having a longitudinally extending slideway, a support for the last at the heel breast adjustable in said slideway, a support for the heel at the back of the last mounted on said base, scales associated with said supports and readable relative to each other for determining the wedge of the heel, a scale-provided slide adjustable in said slideway towards the toe of the last to indicate the spring of the toe, and a slide adjustable in said slideway between said heel breast support and said toe-spring indicating slide and provided with markers for indicating ball measurements of the last.
8. In a last analyzer, a base having a longitudinally extending slideway, a support for the last at the heel breast adjustable in said slideway, a support for the heel at the back of the last mounted on said base, scales associated with said supports and readable relative to each other for determining the wedge of the heel, a scale-provided slide adjustable in said slideway towards the toe of the last to indicate the spring of the toe, a slide adjustable in said slideway between said heel breast support and said toe spring indicating slide, and provided with markers for indicating ball measurements of the last, and an upwardly extending frame adjustable in said slideway and provided with a marker for locating the instep of the last.
9. In a last analyzer, a base having a longitudinally extending slideway, a support adjustable in said slideway, and an instep marker carried by said support.
10. In a last analyzer, a base having a longitudinally extending slideway, a slide adjustable in said slideway, a frame mounted on said slide and adjustable vertically relative thereto, and an instep marker carried by said frame.
11. In a last analyzer, a base having a longitudinally extending slideway, a slide adjustable in said slideway, a frame mounted on said slide and adjustable vertically relative thereto, an arm carried by said frame, and an instep marker carried by said arm and adjustable transversely relative thereto.
12. Apparatus for determining the wedge of the heel of a last under analysis, comprising a scale provided support for elevating the last to the height of the heel that the last will carry, and a second scale-provided support insertable under the heel at the back of the elevated last, and readable in reference to the scale of the first-named support to determine the wedge of the heel.
13. Apparatus for determining the wedge of the heel and the spring of the toe of a last under analysis, comprising a scale-provided support for elevating the last to the height of the heel that the last will carry, a second scale-provided support insertable under the heel at the back of the elevated last and readable with reference to the scale of the first-named support to determine the wedge of the heel, and a scale movable against the toe of the elevating last to determine the spring of the toe.
14. Apparatus for determining the spring of the toe of a last under analysis, comprising a support for elevating the last at the back of the heel to the height of the heel that the last will carry, and a scale-provided support adjustable against the toe of the elevated last to determine the spring of the toe.

In testimony whereof I affix my signature.

MERION LESLIE PREBLE.
